COMBINATION FEATHER DUSTER AND SACHET

David S. McMillan, 166 5th Ave., New York, N.Y.

Filed June 11, 1959, Ser. No. 56,313

Term of patent 3½ years

(Cl. D9—2)

The figure is a front perspective view of a combination feather duster and sachet embodying my new design.

The back of the duster not shown, is substantially the same as the front shown.

I claim:

The design for a combination feather duster and sachet, as shown and described.
